UNITED STATES PATENT OFFICE.

ISAAC FREED, OF HARRISBURG, PENNSYLVANIA.

DESIGN FOR A SLEEPING-CAR SAFE.

SPECIFICATION forming part of Design No. 26,714, dated March 2, 1897.

Application filed November 10, 1896. Serial No. 611,676. Term of patent 14 years.

To all whom it may concern:

Be it known that I, ISAAC FREED, a citizen of the United States, residing at Harrisburg, in the county of Dauphin and State of Pennsylvania, have invented and produced a certain new and original Design for Safe-Fronts; and I do declare the following to be a full, clear, and exact description of the invention, such as will enable others skilled in the art to which it appertains to make and use the same.

My invention relates to a new and useful design for sleeping-car safes; and it consists of a safe of the configuration and ornamentation shown in the accompanying drawings, in which—

Figure 1 is a perspective view of a safe embodying my invention, and Fig. 2 is a transverse sectional view.

The leading feature of my design consists in the rectangular section 1, having a central opening 2, containing a box 14, and provided with a door 10, the windows 4 5, provided with glasses 6 and 7 and of greater height than the central opening 2, over which is arranged an ornamental device. 20 25

What I claim is—

The design for a sleeping-car safe, as herein shown and described.

In testimony whereof I hereunto affix my signature in presence of two witnesses.

ISAAC FREED.
